UNITED STATES PATENT OFFICE.

ROBERT W. STURDY, OF STEPHENSON, MICHIGAN, ASSIGNOR OF ONE-HALF TO CASSIUS W. MC EWAN, OF OMAHA, NEBRASKA.

WRENCH.

1,075,516.

Specification of Letters Patent.

Patented Oct. 14, 1913.

Application filed May 13, 1912. Serial No. 696,933.

To all whom it may concern:

Be it known that I, ROBERT W. STURDY, a citizen of the United States, residing at Stephenson, in the county of Menominee 5 and State of Michigan, have invented certain new and useful Improvements in Wrenches, of which the following is a specification.

This invention relates to improvements in wrenches, and has for its object to provide a wrench of the quick-action class, consisting of few and simple parts so that it may be conveniently and economically manufactured, and will be durable and convenient in 15 use.

Another object is to provide a wrench so constructed that its parts may be readily connected or disconnected, this being desirable so that any one part may be conveniently replaced if injured or broken.

The invention consists of the novel construction, combination and arrangement of parts as described herein and claimed, and as illustrated in the drawing, it being understood that changes in form, size, proportion and minor details may be made within the scope of the claim without departing from the spirit or sacrificing any of the advantages of the invention.

In the drawing Figure 1 is a side view, partly broken, of a wrench embodying my invention. Fig. 2 is a side view of the wrench, the jaws being extended or separated, the handle being broken away. Fig. 3 is a view in longitudinal section of the recessed jaw-member. Fig. 4 is a transverse sectional view of the same, on line 4-4 of Fig. 6. Fig. 5 is a side view of a second jaw-member employed. Fig. 6 is a side view of the wrench to illustrate facility for adjusting the handle and rack-bar as may be desired for gripping larger or smaller objects. Fig. 7 is a plan view of the second jaw-member. Fig. 8 is a view of a threaded 45 pin or pivot. Fig. 9 shows an end portion of the handle, being a front or rear view thereof.

Referring to the drawing for a more particular description, numerals 1 and 2 indicate the two jaws of the wrench, these for convenience being elsewhere designated as first and second jaw-members. Jaw-member 1 is substantially L-shaped and consists of the holding-lug 3 and body-portion 4, the latter being formed with a recess 5 to pro-

vide parallel side plates 6 having free terminals, and parallel, inwardly-projecting ridges 7; and at 8 are indicated elongated apertures, formed opposite to each other in and near the rear part of the side plates. 60 While the outer wall of the jaw-member thus described is of curved or convexed form, this feature is not important any further than that when constructed in this form a required strength is provided without employing surplus material, and said form provides a head for the wrench which will not be obtrusive. It is desirable that the sides of the holding lug 3 and body portion shall be flat, so that when the wrench is disposed flat- 70 wise, said holding-lug may make contact with any object to be gripped or held. Jaw-member 2 preferably is of segment-shape and has a length and thickness corresponding respectively with the length and thickness of holding-lug 3. It is provided on one of its ends with a rack 9, and is formed between its end and rack with a pair of oppositely-disposed, parallel grooves 10. The two jaw-members as thus described may be 80 constructed as separate, integral parts; member 2 may be slidably mounted upon member 1, the rack being disposed in recess 5, ridges 7 engaging within grooves 10. If the second jaw-member is moved in the direction of lug 3, the rack-bar will move 85 inwardly of the recess.

At 11 are indicated parallel bearings consisting of the front walls of the inwardly-projecting ridges 7. 90

At 12 are indicated parallel bearings consisting of the end wall of the second jaw-member which also forms the outer wall of each groove 10, and during the movement of the jaws, each of walls 11 will be in contact 95 with a wall 12 since the ridges engage within the grooves, and therefore any lateral movement of the rack-bar will be prevented.

At 13 is indicated an operating-lever, bar or handle for the wrench. Near its inner end it is provided with trunnions 14, and with a segment gear 15, the longitudinal axis of the trunnions being the center of the gear. The handle is pivotally mounted upon the first jaw-member, the segment gear 100 being disposed within recess 5 and the trunnions engaging in apertures 8 of the side-plates. Since apertures 8 are elongated and extend longitudinally and outwardly from the inner part of the side plates, the trun- 110

nions will be normally disposed in the innermost part of the apertures and the segment gear will normally be disposed in engagement with the rack.

5 Having fully described the several parts and their uses, any extended explanation relating to operation is not necessary. A swinging movement of the handle in one direction or forwardly will cause the jaws 10 to be spaced apart, the rack-bar moving without resistance outwardly of the head of the wrench, the limit of the swinging movement of the handle in this direction being reached when said handle makes engagement with the stop or terminal *a* of the curved wall 16 of jaw-member 1. A movement of the handle in an opposite direction will cause jaw-member 2 to move in the direction of lug 3 to grasp or compress any 20 object disposed therebetween, and, as is obvious, an increase of force thus applied to the handle will result in an increased compression.

By the construction shown, the handle is 25 fulcrumed in the side plates and the leverage may be increased or decreased by respectively decreasing or increasing the distance between the rack-bar and aperture 8 for the pivotal mounting of the handle.

30 The advantages to be derived by the employment of elongated apertures 8 are that the segment gear may be disengaged from the rack bar, temporarily, so that it may be partly rotated without moving the rack-bar, 35 and the angle of the handle may be changed with reference to the rack-bar, as shown by a comparison of Figs. 2 and 6 of the drawing, and this adjustable feature adds materially to the usefulness of the wrench. Also

on account of this construction, jaw-member 40 2 may be conveniently removed from the wrench whenever desired.

The trunnions for the segment gear may be provided by employing the pin *b* shown in Fig. 8. Pin *b* may have a threaded 45 mounting in an aperture (not shown) which may extend through the middle of the segment gear, this being for convenience, when assembling the parts. After the inner end of the handle has been inserted in recess 5, 50 pin *b* may be mounted in the gear, and the wrench will then be ready for use.

Having fully described my invention, what I claim as new and desire to secure by Letters Patent is—

55 A wrench comprising a pair of jaws having sliding engagement with each other, one of said jaws comprising a pair of spaced side walls between which the other of said jaws travels, said last named jaw having a 60 rack formed upon its rear face, an operating handle, a segmental pinion carried by said handle, trunnions projecting beyond the side faces of said pinions, and arcuate slots 65 formed in the said spaced side walls in which said trunnions engage, movement of the handle to open the jaws causing the pinion acting with one of the teeth of the rack as a fulcrum to move out of engagement 70 with said rack to which end said arcuate slots are arranged eccentric to said fulcrum.

In testimony whereof I have affixed my signature in presence of two witnesses.

ROBERT W. STURDY.
